UNITED STATES PATENT OFFICE.

RICHARD FLETCHER VAN HEUSEN, OF NEW YORK, N. Y.

HYGIENIC SHOE-TREE.

No. 921,570.

Specification of Letters Patent.

Patented May 11, 1909.

Application filed March 25, 1908. Serial No. 423,100.

To all whom it may concern:

Be it known that I, RICHARD FLETCHER VAN HEUSEN, a citizen of the United States, residing at New York, in the county and State of New York, have invented certain new and useful Improvements in Hygienic Shoe-Trees; and I do hereby declare the following to be a full, clear, and exact description of the invention, such as will enable others skilled in the art to which it appertains to make and use the same.

My invention relates to a hygienic shoe tree, and is intended to embody in a unitary structure not only the mechanical characteristic advantages of the customary shoe tree, but also to combine therewith the additional function of absorbing from the shoe lining, in connection with which the tree is used, the fermentable organic compounds which tend to remain occluded in the lining and which, to a greater or less extent give off objectionable emanations.

In carrying out my invention I provide the shoe tree with a filling of a material whose capacity for the occlusion of the emanations given off from the shoe lining is far greater than the shoe lining itself. The material that I prefer for this purpose and the one that I contemplate using in practice is charcoal or its equivalent in a finely subdivided condition. To utilize it to advantage for the purposes of the invention, I provide the shoe tree with a hollow interior chamber or cavity lined with a permeable fabric whose interstices are sufficiently small to prevent the sifting out of the powdered charcoal, but sufficiently penetrable to permit the ready infiltration into the mass of the emanations given off from the shoe lining. I also provide the shoe tree with suitable channels, grooves and passages for the ready access of the emanations to the exterior of the inclosing casing or fabric in which the charcoal is contained, and for sufficiently permitting the subsequent giving off of the occluded emanations when the shoe tree is removed and exposed to the air.

I am aware that it has been heretofore proposed to provide a hollow shoe tree with a filling of absorbent cotton and to cause the cotton to absorb a liquid disinfectant supplied to it by means of a pressure bulb, for the purpose of employing the vapors given off by the absorbent cotton impregnated with the liquid disinfectant, for such antiseptic

action as they may be able to exert upon the shoe lining. My invention, however, is radically different from what is proposed in this suggested expedient. By the practice of my invention, instead of attempting to neutralize the fermentable organic matter occluded in the shoe lining during wear, by means of antiseptic vapors given off from the shoe last, I withdraw into the shoe last the occluded organic vapors contained therein by means of a material having a vastly greater capacity for the occlusion of such vapors, and which is itself sufficiently hygroscopic to fully absorb any moisture given off by the shoe lining without its becoming appreciably moist, and which, furthermore, is of such a character that when it is exposed to the air it will as freely give off the absorbed vapors and fully resume its original maximum efficiency. Incidentally, also the material that I employ is readily and homogeneously miscible with sachet powder, lavender, or the like which, employed in reasonably moderate proportions will be found acceptable to the user.

In the accompanying drawing I have shown, for the purposes of illustration only, a convenient form of shoe tree constructed and arranged for carrying my invention into effect; although, it will be clearly understood that this is but one of the many structural embodiments of which the shoe tree, adapted for the carrying out of my invention, is susceptible, and that I do not in any manner restrict myself to the particular form shown in the drawing.

Referring to the drawing, Figure 1 represents a top plan view of the shoe tree selected by me for purposes of illustration, as noted above; Fig. 2 represents a side elevation thereof; Fig. 3 represents a central longitudinal section; and Fig. 4 represents a cross-section taken on a plane indicated by the line 4—4 of Fig. 3.

The shoe tree illustrated may be briefly described as made up of a main body portion *a*, to which the heel portion *b* may be conveniently connected in any suitable way, as for instance, by the slotted plate *c* and the screw *d*, so that the last may be readily inserted within and removed from the shoe; although, as will be readily understood, this particular connection is not of the essence of the invention. The shoe tree is hollowed out, in any convenient or suitable manner,

and is lined with textile fabric *g* within which is contained the powdered charcoal or its equivalent with or without a suitable proportion of sachet powder, lavender, or the like.

It is a characteristic feature of powdered charcoal, in this connection, that it will absorb the noxious emanations from the shoe lining, without withdrawing and occluding the aromatic emanation of the sachet powder. It therefore permits the interchange, by the shoe lining, of the said aromatic emanations for those which are absorbed by the charcoal.

The textile fabric is, as hereinbefore explained, of such weave that its interstices will sufficiently prevent the sifting out of its interior contents, while, at the same time permitting the ready infiltration of the emanations given off from the shoe lining and also the complete subsequent aeration of the mass. For the purpose of obtaining free access of the emanations to the fabric casing and its contents and the equally complete subsequent aeration thereof, I provide the tree with a suitable number of passages, grooves or channels, as shown, to fully subserve this intended purpose. The arrangement of these passages, grooves and channels may, of course, be varied extensively within the limits of good practice, the particular arrangement shown in the drawing being

chosen as illustrative of a satisfactory distribution thereof.

What I claim is:

1. A hygienic shoe-tree, having a cavity lined with a permeable fabric and constituting a container holding a powdered material adapted to absorb and occlude within itself the organic vapors emanating from the shoe lining and which will release said vapors and be restored to its original efficiency upon exposure to the air; and passages connecting the cavity with the surface of the tree substantially as described. 45

2. A hygienic shoe-tree, having a cavity lined with a permeable fabric and constituting a container holding powdered material adapted to absorb and occlude within itself the organic vapors emanating from the shoe lining and which will release said vapors and be restored to its original efficiency upon exposure to the air, and passages connecting the cavity with the surface of the tree in combination with an aromatic powder admixed with said material; substantially as described. 50 55

In testimony whereof I affix my signature, in presence of two witnesses.

RICHARD FLETCHER VAN HEUSEN.
